UNITED STATES PATENT OFFICE.

LOUIS ETIENNE TISSIER, OF BATNA, ALGERIA.

INDUSTRIAL USE OF EXHAUST-GASES OF INTERNAL-COMBUSTION ENGINES.

1,364,656.

Specification of Letters Patent.

Patented Jan. 4, 1921.

Application filed January 19, 1918. Serial No. 212,833.

To all whom it may concern:

Be it known that I, LOUIS ETIENNE TISSIER, citizen of the Republic of France, residing at 28 Boulevard Jules Ferry, Batna, 5 Algeria, have invented new and useful Improvements in Industrial Use of Exhaust-Gases of Internal-Combustion Engines, of which the following is a specification.

The principle of this invention is to employ advantageously the heat of the exhaust of internal combustion engines working with producer gas and more generally internal combustion engines of all descriptions (illuminating gas, kerosene, gasolene, 10 heavy oils, etc.) for the calcination of metallic carbonates (calaminas, iron ores, manganese ores, etc.) as well as gypsum, and even for roasting metallic sulfids, for carbonizing wood, dissociation of peat, and in 15 general for treating all mineral or vegetable matter which undergoes an industrial modification by the agency of heat.

In order to produce this result it suffices to bring the engine exhaust gas under a 25 furnace containing the products to be treated. The exhaust gas circulates from bottom to top in the heating column which is formed in this way, and after a few hours the heat accumulated is sufficient to produce 30 the desired calcination, carbonization or dissociation.

The hot carbonic acid gas of the exhaust acts to dissociate the material under treatment, and after a time it drives off the volatile substances while the non-volatile substances cannot become ignited precisely on account of the presence of inert gas (carbonic acid). In order to carry out this 35 process there is employed a muffler box built 40 of fire-brick and having double or triple the size of the usual muffler box, and the furnace is constructed upon this box.

In the accompanying drawings there are 45 represented in diagram and vertical section, in Figures 1 and 2 two constructional forms of a furnace which allows of carrying out the process according to the invention, in different applications of the same which may occur in practice. It is observed that 50 in the furnace shown in Fig. 1, the exhaust E enters the device at the bottom and at the central part, so that the exhaust takes place from bottom to top. The muffler box R is of cylindrical shape and is at least 55 ten centimeters less in diameter than the furnace part which follows, in order to afford a ledge for the removable perforated metal plate G upon which is placed the product to be exposed to heat. The holes in this plate have a diameter which varies 60 according to that of the product. It can be grasped at the top and removed from the furnace by means of the ring A. The furnace proper is of cylindrical shape, and is built of ordinary firebrick. The walls 65 B are about 0.46 meter thick, with two parts separated by a space of 2 or 3 centimeters filled with wood ash in order to avoid loss of heat. The new process which is the object of this invention is especially 70 applicable to fine products from 1 millimeter to 40 millimeters, and under these conditions the width of the furnace should be about 1 meter (diameter) and about 1.50 meters high. The dimensions will vary according to the size of the ore, etc., to be calcined or roasted. At the level of the 75 perforated plate and situated on a diameter are two furnace openings T made up of cast or wrought iron pipe built into the brick-work and having about 0.20 meter diameter. These are tightly closed on the outside by a heavy metal plate lined with asbestos P. The furnace is charged up to the top. During the action of the exhaust, the charging 80 and the removal of products can be carried on in a continuous manner. After a few hours' run, the lower portions of product are calcined. At this time the doors are 85 opened and the calcined part is removed. Should the material not fall out by its own action, a rake can be used for the removal. According to the size of the engine which furnishes the exhaust, it will require 3 to 4 hours to calcine to a height of 0.40 to 0.60 90 meter of ore, that is, this portion is to be taken out every 3 or 4 hours. Dissociation 95 of carbonates of zinc (calaminas); carbonates of iron or manganese, gypsum, etc., is obtained in nearly all cases by the simple 100 heat of the exhaust, but in case this heat should prove insufficient (roasting of sulfids, calcination of limestone for production of lime); it will suffice to admix a small amount of wood charcoal (0.25 to 1%) in 105 order to obtain a complete result. In order to obtain a better use of the heat of engine exhaust gas, as well as a more economical handling of the products under treatment, the furnace can be constructed with the section shown in Fig. 2. The muffler box R 110 is in cast iron or heavy plate. It is about 0.70

meter high and 0.60 meter in diameter. The lower part of the furnace has 0.63 meter diameter and the roasting plate G (removable perforated plate) has a conical shape. The middle part of the furnace is about 1.10 meters in diameter. The outlet openings are 2 or 3 in number and have a slope of 25 to 27 degrees in order to effect the automatic evacuation of the products as soon as the outlets O are opened, these being formed of iron pipe of 0.15 to 0.20 meter diameter. A tight closing is obtained by a heavy cast iron plate with a screw clamp device. The lower part of the furnace (a b c d) to a height of about 0.80 meter is constructed of plate iron from 6 to 8 millimeters thick, and the outlets are riveted to this plate. Between the brickwork B and the metal part is left a space of 3 or 4 centimeters which is filled with wood ash and serves to allow free expansion.

In order to obtain a better distribution of heat inside the furnace, there is employed a central pipe K of 10 to 12 centimeters diameter open at both ends and which is filled up with material at the same time as the furnace. This pipe rests freely upon the roasting plate G and can be held in place by the material to be treated. It acts to prevent to a certain extent the material in the furnace from forming a compact mass in the central part of the furnace shaft whereby the gas is distributed more uniformly throughout the material, the gas having an opportunity to creep along the wall of the pipe. Said pipe may however be omitted.

The furnace can be constructed entirely in plate iron of 6 to 8 millimeters thickness. In this case a single thickness or course of brick will suffice, but an empty space is always left and filled up with wood ash. When the engines employed are over 60 H. P. size, it is advisable to separate the exhaust in two portions and to construct two furnaces instead of one, using a furnace on each exhaust. In this way, the total efficiency of the system is higher.

The new process also allows of calcining bauxites, kieselguhrs, and in short all ores which are to undergo a dissociation treatment of any kind. When the product under treatment is very friable, as for instance kieselguhr, and has a tendency to run through the holes in the plate, the following arrangement can be made. Instead of disposing the muffler box under the furnace, it is placed within the latter, and the gas exhaust orifice is disposed to open from the top down, and at about 0.50 meter above the roasting plate. This latter is now replaced by a solid plane surface which hermetically closes the lower part of the furnace. Under these conditions the treated products en-

tirely surround the muffler box. The furnace is here built in larger size, especially at the lower part.

Roasting of metallic sulfids is of especial interest in the case of sulfids of zinc (blendes). The size of the pieces to be roasted should be about 3 millimeters. The operation lasts for about 24 hours. The pulsations due to the action of the exhaust gas discharged from the engine into the furnace produce an automatic stirring effect which aids in the roasting process. The transformation of sulfid to oxid of zinc is carried out directly and the material does not pass by the intermediate state of sulfate of zinc, whereas at the present time it has been impossible to avoid the production of sulfate of zinc, and this required a considerable amount of heat in order to effect its final reduction to oxid. By the new process, the roasting is carried on only in the presence of carbonic acid gas (exhaust gas) which acts as an oxidizing agent according to the following reaction.

90

In the usual roasting process, sulfuric acid is produced by reason of a super-oxidation due to the presence of an excess of free oxygen. But in the present case nothing of the kind happens, and this constitutes an entirely new method. It allows of roasting blendes at low temperatures in the presence of carbonic acid alone. The dimensions and shape of the furnace will vary according to the use for which it is employed.

Another application of the use of the heat of exhaust gas of low-carbon gas engines, consists in carbonizing wood, with recuperation of tar. For this purpose there can be employed a furnace of analogous design to Fig. 1. The wood is packed into this furnace. The heat of the exhaust is sufficient to carbonize the wood in a few hours, and it cannot take fire for the reason that it is surrounded by carbonic acid gas (exhaust gas). In this way the wood is perfectly carbonized. The yield in charcoal is about 30 per cent. A furnace of this kind can be constructed with square, rectangular or round section, from 1.20 to 2.80 meters, and a height varying from 3 to 10 meters. The outlets placed at the lower part of the furnace, one or two in number, have the following size, 0.40 meter by 0.70 meter about; they should close hermetically. The top mouth of the furnace is closed by a removable cone-shaped piece in plate iron, and from this passes the piping which brings the gaseous products into a condenser for recuperation of the tar products. To empty the furnace the charcoal produced is allowed to cool, for if removed in a highly heated state it would take fire on contact with the air. A valve is mounted on the exhaust pipe 130

so that the exhaust can escape into the air or be sent into a second furnace.

Having now described my invention, what I claim as new and desire to secure by Letters Patent is:

1. A process for treating mineral or vegetable substances by the heat of exhaust gases of internal combustion engines and which consists in causing said gases to circulate through said substances in direct contact with the latter, substantially as described and for the purpose set forth.

2. A process for treating mineral and vegetable substances by heat, which consists in packing these substances in a shaft furnace, adding to them products designed to facilitate the combustion, and passing internal combustion engine exhaust gases through

this furnace, substantially as described and for the purpose set forth. 20

3. A process for treating mineral or vegetable substances by heat, which consists in packing these substances in a shaft furnace, passing internal combustion engine exhaust gases through this furnace and recovering 25 values from the gaseous products given off, substantially as described and for the purpose set forth.

In testimony whereof I have signed my name to this specification in the presence of 30 two subscribing witnesses.

LOUIS ETIENNE TISSIER.
